UNITED STATES PATENT OFFICE

148,881

DESIGN FOR A SHRINE

John C. Lown, Toronto, Ontario, Canada, assignor, by mesne assignments, to Russell Adam Brown, Toronto, Ontario, Canada

Application May 20, 1947, Serial No. 139,146

Term of patent 3½ years

(Cl. D39—23)

To all whom it may concern:

Be it known that I, John C. Lown, a citizen of Canada, residing at Toronto, in the county of York and Province of Ontario, Canada, have invented a new, original, and ornamental Design for Shrines, of which the following is a specification, reference being had to the accompanying drawing, forming part thereof.

The figure is a perspective view of a shrine, showing my new design. The side of the shrine which is not shown is similar in appearance to the side which is clearly visible, and the back of the shrine is plain and substantially flat.

I claim:

The ornamental design for a shrine, as shown and described.

JOHN C. LOWN.
